UNITED STATES PATENT OFFICE.

EDMUND H. LUNKEN, OF HARTSDALE, NEW YORK.

WINDOW.

Application filed March 5, 1925. Serial No. 13,064.

My invention relates to windows adaptable to wood or metal construction. My object is to provide an effective window, being economical, of attractive appearance, 5 easy to install, and particularly susceptible to variations of ventilations. The window may be made to provide screen storage, and top or bottom ventilation.

In metal windows in particular the formation of weight boxes behind the side stiles, as in usual window construction, is 10 always a problem, because of corrosion. The boxes are all enclosed except at the pulley orifices, and condensation therein is quite 15 destructive. My window is preferably so constructed that the operation is accomplished by means of a counterweight in the form of a cross bar without the use of weight boxes.

20 My window, among other things, is limited to a single sash, but the frame is of the height of the wall into which it is set with the lower portion up to a desired sill height taken up by a transparent or opaque 25 body, whichever is most satisfactory. Thus a wall can be built using my window devices without studding or siding.

Also the upper portion of the frame will 30 be filled with a panel which may be articulated, if desired, to give extra ventilation.

35 Thus it is my object to provide a counterweighted sash without weight boxes in combination with sill pocket and at least partial overhead pocket, for a single sash, thereby permitting full ventilation, a simple manipulating bar, simple installation of sashes by a frame extending from floor to ceiling, and if desired for screen housing.

40 I accomplish my objects by that certain construction and arrangement of parts to be hereinafter more specifically pointed out and claimed.

In the drawings:

45 Figure 1 is a side elevation of the window without screens or sashes in place, said view taken as a central vertical section through sill and cap.

Figure 2 is a like view of Figure 1 showing the screens and sashes in place.

50 Figure 3 is a section on the line 3-3 of Figure 2.

Figure 4 is an elevation (fragmentary) taken from the inside of the window.

Figure 5 is a fragmentary section on the line 5-5 of Figure 1.

55

Figure 6 is an elevation showing the shift-able screen housing element, in lieu of a fixed one.

The stiles of my window are in the form illustrated made of pieces of wood 1, 1, 60 although they may be made of metal formed up as channels or boxes to give proper rigidity. The stiles terminate in a sill 2, preferably at the floor line, and extend up to the ceiling of the room, where they are connected, preferably, by a cap 2^a.

65 Connecting the stiles at the bottom and held permanently in place is a plate 3, which may be formed of metal, wood, or plaster composition, and may be provided with a 70 ground glass light. This panel is exposed to the outside of the building and will be made as a decorative item. It will be of the desired height for safety within the room, which will bring its upper edge to a 75 proper window sill line, in preferred form.

75 As an outside guide strip for the sliding sash I preferably mount a strip 4, which extends full width up to the upper portion of the window, where the top of the sash will 80 lie when closed, where the said strip is narrowed down as at 4^a, to permit of the mounting of an upper transom window section, either fixed or hinged.

85 Extending up from the sill 2 is a parting strip 5 against which the lower fixed plate 3 is mounted. This parting strip is made thicker, by the addition of an upper added section of strip material 6. The space between the strip 4 and the strip 5 forms a 90 slideway for a sliding sash having bottom rail 7, top rail 8, and side rails 9. There will be a suitable weather strip 10 on the outside of the upper rail, and a like strip 11 on the inside of the lower rail.

95

I have indicated a push pin 12 and socket plate 13 for locking the sash in position with its lower rail lapping the top of the plate 3, with the weather strip 11 forming a seal at this point.

100

I have shown a hinged glass window 14 mounted on the stiles by means of a piano hinge 15 extending across the cap. This window when closed is held in place by means of a push pin 16 engaging in a segment shaped retaining bar 17. The bar 17

105

and push pin also permit various held positions of this sash. The sash when closed will abut the portion 4^a of the outer guide strip element, and its rail will engage the weather strip 10 on the upper sliding sash rail.

The hinged relation of this transom window is not a requisite, as it may be fixed in place.

When the sliding sash is pushed down, it 10 will preferably move clear down flush with the top of the plate 3. When it is moved up a portion thereof will lie within the top or transom window section of the frame.

The weight pulley devices are formed of 15 the usual pulleys 18, mounted in housings 19. The housings are fixed at the upper ends of the stiles so that they abut the inside edge of the strip portions 4^a. The upper portion of the portion 6, of the inner guide 20 strips, ends at the lower edge of the pulley housings, and the extra thickness of these portions brings their edges flush with the sides of the said housings.

In addition to the guides mentioned, and 25 referring to an instance in which screens are used, I mount against the strip portions 6, an upper screen, or transom window 20, which is preferably mounted in place by removable screws 21, engaging the strips 6 at 30 each of the two stiles.

I provide two interspaced metal channels 22 and 23, on each stile which are laid with the outer channel 22 abutting the inner face of the parting strip portions 5 and 6, and 35 ending at the lower edge of the pulley housings. In case screens are not used the inner one of the channels is omitted, and the top screen is omitted. Also the top screen may be formed as the hinged element and made 40 as a transom, and the upper transom window made fixed. To illustrate this is not believed to be necessary as it requires a mere shifting of the hinge from one point to another on the underside of the cap.

45 Mounted at the lower portion of the frame, and preferably of the height of the plate 3 is a light plate 24 of plaster board, screening, canvas or whatever may be found desirable, which frame rests as a guide in 50 the space 25 between the two metal channels. Springs 26 at the side edges of this plate will hold it in adjusted position. When lowered this plate forms with the plate 3 a pocket for the housings of the sliding screen.

55 The screen is illustrated at 27, and slides in the outer channel 22. It will be held in position in the usual manner, but a simple form of retaining member will be chains 28 suspended in the channels from above, and 60 merely hooked into eyes 29 on the top of the screen.

The inner channel forms the guideway for the counterweight and manipulating bar. This bar as indicated at 30 has extended 65 ends 31 to guide firmly in the said inner

channel. Weight cords pass from the ends of the bar up over the pulleys and down to the corner of the top rail of the sliding sash. A block 32 is placed in the channel at each side of the frame to engage the bar ends and hold the bar from being moved far enough down to jam the sliding sash up against the top of the window frame. The raising of the bar lowers the sash behind the panel. The positioning of the bar, thus positions the sliding sash at any desired point to give top or bottom ventilation.

It will be evident that departures from the precise stile guiding elements can readily be devised which will serve my purpose. 80 I am aware that sashes counterweighted by cross bars are old, but so far as I am advised no one has utilized this idea with a single sliding sash, with a sill pocket or sash concealing element, and a top transom and 85 weatherproof element. Other modes of counterbalancing could be used, however.

The sliding screen will normally reach from the top of the inner plate 24 to the lower rail of the screen 20. When the 90 screens are omitted, the member 20 need not be employed, and the window frame will not need to be so wide or else the sash, plate 3, and guide strips can be made wider.

Having thus described my invention, what 95 I claim as new and desire to secure by Letters Patent, is:—

1. A window comprising a frame, the lower portion of which is filled by a non-slidable weather excluding cross member, and the upper portion of which is likewise filled by a non-slidable weather excluding cross member, and a sliding sash guided in said frame and adapted in one position to close the space between said two cross members and another sliding closure for the space between said cross members, same being guided in the frame to take a position on the opposite side of the lower cross member from the sash.

2. A window comprising a frame, the lower portion of which is filled by a weather excluding cross member, and the upper portion of which is likewise filled by a weather excluding cross member, and a sliding sash guided in said frame and adapted in one position to close the space between said two cross members, pulleys mounted with their bodies at right angles to the sliding sash, and a cross bar for counterweighting the sash, connected by cords with the sash, and guided for sliding in the said window frame.

3. A window comprising a frame, the lower portion of which is filled by a weather excluding cross member, and the upper portion of which is likewise filled by a weather excluding cross member, and a sliding sash guided in said frame and adapted in one position to close the space between said two

cross members, said sash being so guided and the cross members so mounted that the sash slides outside of the lower member and inside of the upper member.

5 4. A window comprising a frame, the lower portion of which is filled by a weather excluding cross member, and the upper portion of which is likewise filled by a weather excluding cross member, and a sliding sash guided in said frame and adapted in one position to close the space between said two cross members, said lower member being of substantially the height of the sash and an additional means movable in the frame from 10 70

15 a position inside the lower cross member and concealed from without thereby to a position of closing the opening between said cross members.

5. A window comprising a frame, the lower portion of which is filled by a weather excluding cross member, and the upper portion of which is likewise filled by a weather excluding cross member, and a sliding sash guided in said frame and adapted in one 20 85 position to close the space between said two cross members, said lower member being of substantially the height of the sash, and the frame arranged in the building so that its sill member is at the floor line of the room 25 90

30 in such building and a sliding panel in said frame normally located adjacent to and of the shape and size of the lower cross member.

6. A window comprising a frame, the lower portion of which is filled by a weather excluding cross member, and the upper portion of which is likewise filled by a weather excluding cross member, and a sliding sash guided in said frame and adapted in one 35 100 position to close the space between said two cross members, said frame being located so as to bring the lower edge of the lower cross member substantially to the floor line of a room in which the frame is mounted, a screen 40 105 located slidably in the frame, and an additional cross member in the upper portion of the frame against which the screen abuts, with its lower edge adjacent the top of the lower cross member.

50 7. A window comprising a frame, the lower portion of which is filled by a weather excluding cross member, and the upper portion of which is likewise filled by a weather excluding cross member, and a sliding sash guided in said frame and adapted in one 55 110 position to close the space between said two cross members, an additional cross member in the lower portion of the frame to form a pocket with the first mentioned cross member, and a screen mounted in the frame to slide into said pocket in one position thereof.

8. A window comprising a frame, the lower portion of which is filled by a weather excluding cross member, and the upper portion of which is likewise filled by a weather

excluding cross member, and a sliding sash guided in said frame and adapted in one position to close the space between said two cross members, an additional cross member in the lower portion of the frame to form a pocket with the first mentioned cross member, and a screen mounted in the frame to slide into said pocket in one position thereof, and an additional cross member in the upper portion of the frame to fill the same down to a line of juncture with the said screen, when same is raised with its lower edge in juxtaposition with the upper edge of the pocket so formed.

9. A window comprising a frame, the lower portion of which is filled by a weather excluding cross member, and the upper portion of which is likewise filled by a weather excluding cross member, and a sliding sash guided in said frame and adapted in one position to close the space between said two cross members, an additional cross member in the lower portion of the frame to form a pocket with the first mentioned cross member, and a screen mounted in the frame 85 90 to slide into said pocket in one position thereof, said additional cross member being slidably mounted in the said frame.

10. A window comprising a frame, the lower portion of which is filled by a weather excluding cross member, and the upper portion of which is likewise filled by a weather excluding cross member, and a sliding sash guided in said frame and adapted in one position to close the space between said two cross members, pulleys mounted with their bodies at right angles to the sliding sash, and a cross bar for counterweighting the sash, connected by cords with the sash, and guided for sliding in the said window frame, 100 and means for stopping the movement of the weight bar short of position to jam the sliding sash against the top of the window.

11. A window comprising a frame, the lower portion of same filled by a weather excluding cross member and the upper portion of same filled by two spaced cross members, a sash and a screen slidable in said frame, both of same closing the opening between said members, and guided in the 110 frame so as to wipe the lower cross member, and abut each one of the two spaced upper members.

12. A window comprising a frame, the lower portion of same filled by a weather excluding cross member and the upper portion of same filled by two spaced cross members, a sash and a screen slidable in said frame, both of same closing the opening between said members, and guided in the 120 frame so as to wipe the lower cross member, and abut each one of the two spaced upper members, the outer of the two upper cross members being articulated in the frame.

EDMUND H. LUNKEN.
